Attorney

UNITED STATES PATENT OFFICE.

LOUIS W. MEYERS, OF CHICAGO, ILLINOIS.

APPARATUS FOR BACKING BOOKS.

Application filed September 19, 1924. Serial No. 738,713.

To all whom it may concern:

Be it known that I, LOUIS W. MEYERS, a citizen of the United States, residing at Chicago, in the county of Cook and State of Illinois, have invented certain new and useful Improvements in Apparatus for Backing Books, of which the following is a specification.

This invention relates to the manufacture 10 and repairing of books, and more particularly to a machine for backing books.

In backing books of different thicknesses, the radius of the curve on the back of the book varies according to the thickness of 15 the book and it is desirable to provide some means for automatically adjusting the backing roller to books of different thicknesses.

In the present invention, I provide a machine having a backing roller and means for 20 automatically adjusting the radius of the roller according to the thickness of the book.

More specifically, I provide a vise adjustable on the bed of the machine adapted to receive the book to be backed and a frame in 25 which the backing roller is mounted, the frame being pivotally mounted on rollers and being connected to the two jaws of the vise by links, whereby the pivot of the frame will change as the jaws of the vise are moved 30 with respect to each other.

In the accompanying drawings, I have shown one embodiment of the invention. In 35 this showing:

Figure 1 is a front elevation of the machine,

Figure 2 is a horizontal sectional view of a portion of the machine on line 2-2 of 40 Figure 1,

Figure 3 is an end elevation,

Figure 4 is a vertical sectional view 45 through the roller elevating means on line 4-4 of Figure 3, and,

Figure 5 is an end view of a book before and after backing.

Referring to the drawings, the reference 50 numeral 1 designates the legs of the machine adapted to receive and support a bed 2. A vise is mounted on the bed and it consists of a stationary jaw 3 having a vise plate 4 arranged thereon and a movable jaw 5 having a vise plate 6 arranged thereon. The movable jaw is provided with a nut 7 secured to its rear face by means of bolts 8 and a vise screw 9 passes through this nut. 55 The screw is mounted in a suitable bearing

10 and is provided with a hand wheel 11 at its outer end to permit adjustment of the movable jaw. The book to be backed is arranged on the bed of the machine between the jaws of the vise, as indicated in dotted lines at A in Figure 3 of the drawings.

The backing roller is mounted in a frame, consisting of side members 12. These side members are pivotally mounted on the pins or rollers 13. The rollers 13 are connected 65 to the inner ends of compensating links 14 and the outer ends of these links are pivotally mounted on pins or bolts 15, carried by the two jaws of the vise. A counterweight 16 is arranged beneath the pivot 13. 70 A shaft 17 is mounted in the top of the frame, being supported in suitable bearings 18 and this shaft is provided with a hand wheel 19 on its outer end. Bevel gears 20 are secured to the shaft adjacent each end 75 and these gears mesh with similar bevel gears 21 mounted on the upper ends of vertical shafts or screws 22. The upper shaft 17 is provided with a retaining collar 23 which is secured thereto by means of a pin 80 24 and is adapted to prevent longitudinal movement of the shaft.

The shafts 22 extend downwardly to a point adjacent the pivots 13 and are provided with threaded portions 25. These threaded portions extend through nuts 26 carried by roller boxes 27. A roller 28 is arranged between the roller boxes and a bushing 29 is arranged in each end of the roller. The bushing is adapted to receive a shaft 30, the 90 end of which is received in the roller box.

In operation, the book to be backed is first formed, as shown at B in Figure 5 of the drawings and has a straight rear edge 31. It is then arranged in the vise in the usual 95 manner, as shown in Figure 3 of the drawings and is clamped in position by means of the hand wheel 11. It will be apparent that the movement of the jaws of the vise causes the compensating links 14 to move, 100 outward movement of the jaw 5 tending to cause the links to assume a horizontal position, and inward movement of the movable jaw causing the links to assume an inclined position and raising the pivot pins 13. 105 After the book has been clamped in the vise, the roller 28 is lowered through the medium of the hand wheel 19, the shaft 17, and the screws 25. When the roller engages the back of the book, the frame is swung on the pivots 110

13, as indicated in dotted lines in Figure 3 of the drawings. This rolls the back of the book in the desired manner and forms a book, as indicated at C in Figure 5 of the drawings, having the back edge rolled, as indicated at 32. It will be apparent that the pivot pins 13 will move upwardly as the jaws of the vise approach each other and the arc traveled by the roller in engagement with the back of the book will decrease in proportion to the proximity of the jaws to each other. By the employment of links 14 of proper size, the adjustment of the radius may be in accordance with the standard practice to give the desired radius to books of different thicknesses. As the links 14 are of the same length, the pivots 13 will be at an equal distance from the jaws of the vise at all times.

20 It is to be understood that the form of my invention herewith shown and described is to be taken as a preferred example of the same, and that various changes in the shape, size, and arrangement of parts may be resorted to without departing from the spirit of the invention or the scope of the subjoined claims.

I claim:

1. In a device of the character described, 30 a vise, a frame pivotally mounted over said vise, a vertically adjustable roller carried by said frame, and means controlled by the movement of the jaws of the vise for shifting the pivot of the frame.

2. In a device of the character described, 35 a vise, a frame arranged adjacent said vise, a vertically adjustable roller carried by said frame, links connected to the jaws of said vise, and pivot pins carried by said links and supporting said frame. 40

3. In a device of the character described, a vise, a frame pivotally mounted over said vise, a horizontally extending shaft carried by said frame, vertically extending shafts arranged at opposite sides of said frame and 45 connected to said horizontally extending shaft to be rotated thereby, said shafts being provided with threaded portions, roller boxes mounted on the threaded portions of said shaft, and a roller arranged between said 50 boxes and supported thereby to permit rotation.

4. In a device of the character described, a vise, links connected to the jaws of said vise, pivot pins connected to the ends of 55 each pair of links, a frame pivotally supported on said pins, a horizontally extending shaft arranged in the top of said frame, vertical shafts arranged at each side of said frame and connected to said horizontally extending shaft to be rotated thereby, said shafts being provided with threaded portions, and a roller arranged between said 60 shafts and adapted to be vertically adjusted by the rotation of said shafts. 65

In testimony whereof, I affix my signature.

LOUIS W. MEYERS.
